Inventor:

W. C. Evarts

United States Patent Office.

WASHINGTON C. EVARTS, OF DANBY, NEW YORK.

Letters Patent No. 66,958, dated July 28, 1867.

IMPROVEMENT IN PLOUGH.

The Schedule referred to in these Letters Patent and making part of the same.

TO ALL WHOM IT MAY CONCERN:

Be it known that I, WASHINGTON C. EVARTS, of Danby, Tompkins county, New York, have invented an Improved Plough; and I do hereby declare that the following is a full and exact description thereof, reference being had to the annexed drawings and the letters thereon.

My object is to make a plough with hinged or winged mould-boards, and fit it for various uses. This I accomplish in the form I prefer, by making a double point which penetrates the earth and throws it partially up and to each side, when the mould-boards receive it, and either spread it evenly or move it at intervals on each side of the furrows. The spreading evenly is done by setting the hinged mould-boards so as to clear a cam-wheel soon to be named. The moving the earth at intervals is done by a wheel just back of the mid-rib of the cast-iron beam. This wheel is roughened so as to make adhesion to the ground, and has cams on its sides, which at intervals throw the hinged mould-boards, and with them the earth, outwards. A spring or lips on the cams retract them. By this means a vibratory action is had at times and in ways such as are desirable for various uses. Changing the wheels gives various cams for various purposes, and changing the mould-boards gives various sizes and forms for various uses. These and other facts are apparent in the drawings, which are—

Figure 1, a side view of my plough.

Figure 2, a side view with one wing or mould-board removed, showing the internal structure.

Figure 3 the mould-board hinges; and

Figure 4 the fastening of the mould-boards clear of the wheel.

In fig. 1, A A are the handles; B the beam, which also makes the frame of the plough, and by the mid-rib part of it, the path for the wheel D; and C is the point; E are the hinged mould-boards, and D the cam-wheel that moves the mould-boards. In fig. 2 the same letters refer to the same parts. At II is a set-bolt in a slot in the frame-piece F, which is hinged at G. By these means the wheel can be raised or lowered, and also one wheel taken out and another put in its place. The cams P P, &c., act on friction-rollers or on surfaces, at any convenient place on the inside of the mould-boards, and thus produce the vibrations of them. At I is the rod for the hinge of vibration through ears J J on the adjustable frame R R, of which frames there are various sizes for various-shaped mould-boards. These frames are attached by set-screws to the mid-rib of the plough-frame. At M is a projecting hook or stay, N, which locks in a hole in one of the frame-pieces F, or other convenient place. This is for the purpose of fixing the mould-boards clear of the cam-wheel D when desirable. In fig. 3 it is only further necessary to notice that the mould-board E laps back of the point C, so that it makes a shedding joint, and that as stated various-sized and shaped mould-boards are easily taken off and put on the plough for various uses. In fig. 4 the locking of the mould-boards clear of the cams of the wheel is more clearly seen. With the fixed position of the mould-boards the plough is a simple cultivator, as of corn, for example, or a double wide-furrow plough with suitable mould-boards, a horse-hoe, and a surface drag. With the wheel in action it hills corn, potatoes, and other articles, and with a riddle or other mould-board, throws out potatoes in digging them, as well as has other acts and uses. The other uses and parts of my plough are apparent to those skilled in the art to which it appertains.

Claim.

1. I claim making a plough with the hinged mould-boards E E, cam-wheel D attached to the mid-rib or beam-frame, or other convenient part, and actuating the same as and for the purposes described.
2. I claim making the cam-wheel D adjustable by means of the hinged and slotted pieces F F, for the purposes described.
3. I claim hanging the mould-boards on a separate and adjustable frame R R, for the purpose of using thereby various-sized and shaped mould-boards for various uses, as described.
4. I claim lap-hinging the various mould-boards so far back of the plough point as entirely to conceal the hinges and protect them from the earth as it slides over the joint, as described.
5. I claim extending the mid-rib of the beam-frame B to near the wheel D, and so shaping the same in combination with the wheel as to make an even and smooth path for the wheel D, for the purpose of giving an even, steady motion to the cam-wheel, as described.
6. I claim the combined whole, when virtually made and operated as described, for the purposes of double wide-furrow plough, cultivator, and digger, as set forth.

WASHINGTON C. EVARTS.
